ATTORNEY

UNITED STATES PATENT OFFICE

AIRLIE E. STEPHEN, OF LOS ANGELES, CALIFORNIA

HAIR-ORNAMENT DEVICE

Application filed September 27, 1927. Serial No. 222,227.

My invention relates to a hair ornament pin or device which is particularly adapted to be secured to the hair at the parting, or parting line thereof.

5 The objects of my invention are: first, to provide a novel hair ornament pin or device which may be positioned and secured at, over, or over a portion of the parting, or hair parting portion of the hair; second, to 10 provide a device of this class which is provided with a double pin so that the same may be secured to separate portions of the hair particularly adapting the same to be placed over the portion of the head having 15 no hair; third, to provide a device of this class which, by reason of its double pin construction, is adapted to prevent the ornament from tilting; fourth, to provide a device of this class which, by reason of its double pin 20 construction, is applicable for ornaments in general for holding the same in the desired positions; fifth, to provide a hair ornament pin having a pin portion so constructed as to prevent longitudinal movement of the 25 pin; sixth, to provide a device of this class having a double pin portion and in which the separate pin portions are connected together near their pivotal ends so that the separate pin portions act in unison and 30 whereby the connecting portion serves as spring means for holding the free or pointed ends of the pin portions resiliently within the clasps; seventh, to provide a device of this class in which the pin portion of the 35 device at one end of the pivotal connection to the ornamental portion of the device also serves as a portion of the ornament of the device; eighth, to provide, as a whole, a 40 novelly constructed hair ornament pin or device; and, ninth, to provide a device of this class which is very simple and economical of construction, durable and which will not readily get out of order.

With these and other objects in view, as 45 will appear hereinafter, my invention consists of certain novel features of construction, combination and arrangement of parts and portions, as will be hereinafter described in detail and particularly set forth in the 50 appended claims reference being had to the

accompanying drawings and to the characters of reference thereon which form a part of this application in which:

Figure 1 is a portrait view of a woman's head showing my hair ornament pin in one 55 form of construction secured at the parting portion of the hair of the woman's head; Fig. 2 is a top view of the hair ornament pin in one form of construction; Fig. 3 is an 60 edge view thereof showing by dotted lines the pin portion unclasped; and, Figs. 4 and 5 are transverse sectional views thereof taken, respectively, on the lines 4-4 and 5-5 of Fig. 2.

Like characters of reference refer to similar parts and portions throughout the several views of the drawings.

My device consists essentially of an ornament member 1, a pin member 2, a pivot pin 3, and clasp members 4.

The ornament member 1 may be made in innumerable designs, but the same is preferably long and narrow, the width being preferably such as to reasonably cover the parting portion of the hair and may also 75 extend a considerable distance to either side of said portion. The ornament member is preferably curved upwardly, as shown in Fig. 3, so as to conform somewhat to the contour of the head at the parting portion 80 of the hair although the same may be curved considerably more than such contour, if desired. The outer side of the ornament portion member 1, which portion is exposed to view, is provided with the ornamental design desired.

The pin member 2, as shown in the drawings, is made preferably in the form of a conventional bone or celluloid hairpin with a bowed or looped outer end 2^a which, in my 90 construction, serves simultaneously as an ornamental portion of the device as well as a spring portion thereof for the two pin portions or prongs 2^b which extend along the lateral edges of the ornament member 1. 95 This pin member 2 is provided with waves or corrugations 2^c in its pin portions or prongs so that the ornament will be retained in the hair against longitudinal movement. The inwardly extended corrugations of the 100

prongs nearest the loop portion 2^a, indicated by 2^d, are pivotally connected to one end of the ornament member by a pivot pin 3 which extends transversely through the prongs and through the one end of the member 1, as shown in Figs. 2, 3 and 4. A slight lateral play is preferably provided on the pivot pin 3 to permit the prongs 2^b to move inwardly and outwardly slightly so as to permit the 10 resilient loop portion 2^a to effect a spring action for forcing the free or pointed ends of the prongs 2^b outwardly from the ornament member 1. The outer side of the loop portion 2^a may be provided with jewels or 15 stones, or designs of any desired description.

In order to provide symmetry in the design, the opposite end of the ornament member 1 may be also provided with a loop portion 5 of similar design, said loop portion 5 being preferably fixedly secured to said opposite end. It will be noted that when the device is positioned and secured in the hair, the prongs of the pin member are concealed below the hair; therefore, both ends of the 25 ornamental device will appear symmetrical.

Intermediate the ends of the ornament member 1, are provided clasps 4 which extend laterally from the lateral sides of the ornament member and are formed as hooks 30 with their hook portions extended downwardly and inwardly, as shown best in Fig. 5. These clasps 4 may be made from a single member extended transversely through the ornament member 1 with hook portions at its opposite ends, as shown in Fig. 5. These 35 clasps retain the pin portions or prongs 2^b in position and substantially against the lateral sides of the ornament member, as shown in Fig. 2.

It will be here noted that, if desired, the 40 loop portions at the ends of the ornament member, namely the portions 2^a and the member 5, may be eliminated, and, if it is desired to connect the two prongs of the pin member, said connecting portion may also 45 serve as the pivotal portion or mounting of the pin member and still serve as a resilient connecting portion.

Though I have shown and described a 50 particular construction, combination and arrangement of parts and portions, I do not wish to be limited to this particular construction, combination and arrangement, but desire to include in the scope of my invention 55 the construction, combination and arrangement substantially as set forth in the appended claims.

Having thus described my invention, what I claim as new and desire to secure by Letters Patent is:

1. In a device of the class described, an ornamental member, a pin member connected at one end thereto and provided with a pair of prongs extending to and adapted to 65 engage the opposite lateral sides of the orna-

mental member, and means for clasping the prongs at their ends to the side portions of the ornamental member.

2. In a device of the class described, an ornamental member, and a pair of prongs 70 connected at one end to and adjacent one end of the ornamental member and extending with their free ends toward the opposite end of the ornamental member and clasped to the middle portion of the latter forming 75 a pin having a short securing portion relative to the whole length of the ornamental member.

3. In a device of the class described, an ornamental member, a pin member, said pin member comprising a pair of pointed prongs and a loop portion connecting said prongs at one end, and a pivot pin connecting said prongs immediately inwardly from said loop portion to the opposite lateral sides of 80 said ornamental member.

4. In a device of the class described, an ornamental member, a pin member, said pin member comprising a pair of pointed prongs and a loop portion connecting said prongs at 85 one end, and a pivot pin connecting said prongs adjacent said loop portion to the opposite lateral sides of said ornamental member, the pivot portions of the ends of said pivot pin being extended beyond the lateral sides of said prongs to permit lateral movement thereof relative to each other and to said ornamental member.

5. In a device of the class described, an ornamental member, an ornamental loop portion fixed at one end thereof, another ornamental loop portion pivotally mounted at the opposite sides of its open portion on the opposite end of the ornamental member, and forming a portion symmetrical to the fixed loop portion, both loop portions extending beyond the end of the ornamental member, the pivoted loop portion having prongs extended therefrom along said ornamental member toward the other loop portion, the pivoted loop portion being adapted to extend around the end of the ornamental member to which it is secured when the prongs are opened from the ornamental member.

6. In a device of the class described, an ornamental member, an ornamental loop portion fixed at one end thereof, another ornamental loop portion pivotally mounted at the opposite sides of its open portion on the opposite end of the ornamental member, and forming a portion symmetrical to the fixed loop portion, both loop portions extending beyond the end of the ornamental member, the pivoted loop portion having prongs extended along the lateral sides of the ornamental member and clasped intermediate its ends to and against the lateral sides of the ornamental member, the pivoted loop portion being adapted to 120 125 130

extend around the end of the ornamental member to which it is secured when the prongs are opened from the ornamental member.

7. In a device of the class described, an ornamental member, and a prong member pivotally mounted near one end at the opposite lateral sides of said ornamental member, said prong member having prongs provided intermediate their ends with corrugations, the inner corrugations of the prong member being adapted to be positioned against the lateral sides of the ornamental member.

In testimony whereof, I have hereunto set my hand at Los Angeles, California, this 20th day of September, 1927.
